CLAIM

The ornamental design for a shower head as shown and described.

DESCRIPTION

FIG. 1 is a perspective view of a shower head according to an embodiment of our design;

FIG. 2 is another perspective view thereof at a different aspect;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of a shower head is included for the purpose of illustrating portions of the article and forms no part of the claimed design.
